UNITED STATES PATENT OFFICE.

ADOLPHUS F. GIBBONEY, OF BELLEVILLE, PENNSYLVANIA.

GRAIN AND GRASS-SEED DISTRIBUTER.

SPECIFICATION forming part of Letters Patent No. 258,407, dated May 23, 1882.

Application filed January 7, 1882. (Model.)

To all whom it may concern:

Be it known that I, ADOLPHUS F. GIBBONEY, of Belleville, in the county of Mifflin and State of Pennsylvania, have invented a new and 5 Improved Grain and Grass-Seed Distributer; and I do hereby declare that the following is a full, clear, and exact description of the same, reference being had to the accompanying drawings, forming part of this specification, in which—

Figure 1 is a rear elevation with the hopper in section. Fig. 2 is a plan view, and Fig. 3 is a vertical longitudinal section.

My invention relates to improvements in 15 that class of seeding-machines known as "force-feed" seeding-machines; and it consists in the peculiar construction and arrangement of the parts, as hereinafter more fully set forth.

20 In the accompanying drawings, *a* represents a part of the frame of a seeder, to the upper face of which a hopper, *b*, of the usual construction is secured.

c represents a seed-cup secured to the lower 25 face of the frame under the throat or lower end of the hopper *b*. The seed-cup *c* is provided with an opening, *d*, for the passage of the grain, having a slanting lip or lower edge, *e*. One of the sides of the seed-cup *c* is pro-

30 vided with a circular orifice, *h*, which serves as a bearing in its revolutions for the cut-off or sleeve *i*, the latter also being adapted to slide in the bearing *h*. The cut-off *i* consists of a short hollow cylinder, corrugated on its interior 35 surface, and adapted to engage with and turn the corrugated feed-wheel *k*, which forms a part of a sleeve, *l*, provided with a circumferential groove, *l'*, journaled in one side of the seed-cup, and a collar, *l''*. The sleeve *l*, of

40 which the feed-wheel *k* forms a part, is slipped on the shaft *m*, the cut-off *i* being also secured to the shaft *m*. *m'* is a stop-pin passing through the shaft *m*, and extending out on both sides to limit the play of the cut-off in one direction, 45 its play in the opposite direction being limited by a stop secured to the under face of the frame *a*, against which the inner end of the cut-off abuts in its reciprocations. By this construction, it will be seen, the feed-wheel and

50 cut-off, being connected together by the en-

gagement of their corrugation, will revolve together in the seed-cup with the shaft *m*, and at the same time the latter may be slid back and forth by a lever connected therewith, thereby causing the cut-off to slide back and forth on the feed-wheel, and thereby increasing or diminishing the quantity of grain sown as desired. The lower edge or lip, *e*, of the opening *d* in the seed-cup *c* for the discharge of the grain is, as before stated, slanting or oblique to the corrugations in the feed-wheel *k*, whereby as the feed-wheel revolves, causing the force-feed, each of its buckets or cups commences discharging the grain at the lower end of the slanting lip *e*, and thence upwardly, 65 thus distributing the grain evenly.

The side of the seed-cup *c* opposite its opening *d* is provided with an inclined triangular flange, *n*, for the purpose of guiding the grain from the hopper to the side of the feed-wheel 70 opposite the cut-off. The guide-flange *n* also serves, in the revolution of the cylindrical cut-off *i*, to remove grain from its periphery and deliver it to the feed-wheel. In the distribution of the seed the latter falls from the hopper on one side of the feed-wheel and revolves it, carrying the seed to the slanting lip at the discharge-opening of the seed-cup, which opening is increased or lessened, as desired, by the cut-off. 75

What I claim as my invention is—

1. The cup *c* and flange *n*, in combination with the sliding cut-off *i*, whereby the flange performs the double purpose of guiding the grain and scraping the cut-off, substantially 85 as described.

2. The combination, with the hopper *b*, seed-cup *c*, provided with the guide-flange *n* and opening *d*, having a slanting lip, *e*, sliding shaft *m*, cylindrical corrugated cut-off *i*, fast thereon, and feed-wheel *k*, substantially as described, 90 and for the purpose set forth.

The above specification of my invention signed by me in the presence of two subscribing witnesses.

ADOLPHUS FRANKLIN GIBBONEY.
